UNITED STATES PATENT OFFICE.

STEPHEN JARVIS ADAMS, OF PITTSBURG, PENNSYLVANIA, ASSIGNOR TO
MARCELLIN C. ADAMS, OF PITTSBURG, PENNSYLVANIA.

SAND-MOLDING APPARATUS.

SPECIFICATION forming part of Letters Patent No. 697,385, dated April 8, 1902.

Application filed March 30, 1897. Serial No. 629,917. (No model.)

To all whom it may concern:

Be it known that I, STEPHEN JARVIS ADAMS, a resident of Pittsburg, in the county of Allegheny and State of Pennsylvania, have invented a new and useful Improvement in Sand-Molding Apparatus; and I do hereby declare the following to be a full, clear, and exact description thereof.

My invention relates to apparatus for forming sand molds, and more especially to that class in which the sand is compacted around the pattern and within the flask or within the core-box by jarring.

The invention relates to certain improvements upon the Letters Patent No. 210,393, granted to me December 3, 1878.

As this invention has been practiced it has been found that where a shallow reservoir holding the sand above the flask was employed without any follower of any kind the sand would rebound, both within the upper part of the flask and within the reservoir above the same, so that it was impossible to compact the upper part of the mold as firmly as the lower part thereof. It was also found, however, that where the follower or weight, such as shown in said patent, was employed it would cant and bind within the reservoir and was difficult to handle properly, while unless a heavy weight were employed it was affected by a tendency to rebound, and therefore that perfect accurate work could not be performed. In operating this class of machinery by power apparatus it has always been found that where the power was not applied in a direct line central with the jarring-table and having a straight vertical movement there was great liability of the sand jarring slightly to one or the other side and packing more solidly against one side of the flask or against one side of the pattern than against the other side, leaving the sand on the other side sufficiently loose and spongy to be pressed out by the metal and forming a swell or enlargement upon the casting. It was also found practically impossible to form shallow molds by this jarring process on account of the rebound of the sand above described and the difficulty of holding the sand to place or of distributing it evenly over the pattern, while the side movement of the jar-

ring-table above referred to affected the body of sand, the jar giving a "whip-stroke," as it might be described, which caused the sand to move to one side of the flask or reservoir, 55 there being no means of holding it directly over that portion of the pattern against which it was intended to pack it. These difficulties are overcome by the apparatus herein described, some of the features of which may 60 be briefly stated as follows: To provide for the even packing of the sand and to prevent the rebound thereof, I provide a guided mold-follower which enters the reservoir as the sand is jarred down therein and holds the 65 sand from rebound, this being assisted materially by a follower holder or retainer which prevents backward movement of the guided follower. This guided follower is also preferably arranged with a recess corresponding 70 substantially to the shape of the pattern, so that it will provide for a more even packing of the sand throughout the mold, this being especially of advantage in the formation of shallow molds. To obtain the direct vertical 75 jar, I have formed a central guideway through the anvil on which the jarring-table strikes to impart the jar to the mold and have provided a lifting-bar extending upwardly through this anvil, the power for raising the 80 table being applied to the lifting-bar below the anvil.

In the forming of a mold the regular practice has been to impart to the same a series of jars of substantially the same length; but 85 I have found that a better mold can be formed by employing jars of short length in the first part of the operation, and thereby distributing the sand throughout the mold, and then following such short jars with one or more 90 longer jars, which will act to compact the sand evenly within the mold after the distributing thereon by the short jars.

My invention comprises certain other improvements, which will be hereinafter fully 95 set forth and claimed.

To enable others skilled in the art to make and use my invention, I will describe the same more fully, referring to the accompanying drawings, in which—

Figure 1 is a side view, partly broken away, of apparatus embodying the invention, the

jarring-table being raised. Fig. 2 is a like view, the jarring-table resting on the anvil or block and the parts being shown in their usual positions when the mold is compacted.

5 Fig. 3 is a cross-section through the anvil-block at 3 3, Fig. 2, showing the guiding devices for the guide-post or lifting-bar. Fig. 4 is a detailed perspective view showing the way of connecting the yoke to the jarring-table. Fig. 5 is a side view, partly broken away, of a modification of the apparatus, showing a different way of lifting the jarring-table and of holding the guided follower from backward movement; and Fig. 6 is a side view 15 showing another form of follower provided with means for the guiding of the same.

Like letters indicate like parts in each of the figures.

The apparatus embodying the invention 20 may include different forms, such as the several forms illustrated in the drawings; but that shown in Figs. 1 to 4 is the preferable form, and I will give a more detailed description of it.

25 The operative mechanism to be hereinafter described is located under the working floor *a*, and the anvil or jarring-block *b* rests on this floor, having the guide-passage *b'* formed centrally thereof and passing vertically 30 through the same, through which the lifting-bar *c* passes, said bar carrying at the upper end the jarring-table *d*, the lifting-bar *c* being secured to the table at the center thereof, so that it will lift the same and impart a per- 35 cent vertical jar thereto, the lifting-bar *c* being guided within the guideway *b'* of the jarring-block. Resting on the jarring-table *d* is the pattern-plate *e*, carrying the pattern *e'*, around which is the flask *f*, while resting 40 upon the flask is the reservoir *g*, the flask and reservoir being held in line in any suitable way, such as the guides *g'*. Above the reservoir and adapted to enter the same as the sand is jarred downwardly is the guided fol- 45 lower *h*, which in the construction shown in Figs. 1 to 3 is mounted in the yoke *k*, which yoke carries the guideway *k'* for the guided follower. Under the floor or working platform *a* is the mechanism for lifting the bar *c*, 50 this mechanism in Figs. 1 and 2 being shown as a cam of peculiar form, which is shown at *l*, and being mounted on the standards *i* and bearings *i'*. These are the general features of the apparatus, and I will now proceed to 55 describe the same more in detail.

The anvil-block *b* is preferably of metal, the guideway *b'* being cast or drilled therein, and in the preferable construction suitable guide-blocks *b''* extend in seats *b''*, formed 60 therefor in the block, and provide for accurate adjustment for the lifting-bar *c*, and thereby insure accurate vertical movement of the same. I generally employ a set of guide-blocks *b''* near the upper end of the anvil-block and a like set near the lower end thereof.

65 It will be noticed that the lifting-bar *c* is an-

gular, and the inner ends of the guide-blocks *b* therefore fit this angular bar. The body portions of the guide-blocks *b''* are preferably cylindrical in shape and fit in like-shaped 70 seats in the anvil-block, and they may be adjusted and locked in any suitable way, such as by adjusting-screws *b⁴*, bearing against the ends of the guide-block and passing through yokes *b⁵*, extending out from the blocks, or by 75 set-screws *b⁶*, or in other ways well known to the skilled mechanic. In this way the power for lifting the jarring-table is applied centrally thereof, and the lifting-bar can be so adjusted as to give absolutely vertical move- 80 ment in raising the jarring-table and guiding it in its descent.

It will be noticed that the lower end of the lifting-bar *c* extends below the platform *a* and carries the antifriction-roller *c'*, which engages with the faces of the cam *l* and by which the lifting-bar is raised. To prevent side strain upon the bar, I employ the two standards *i*, mounting the cam *l* in bearings *i'* upon these standards, so that it rotates between the 90 same, while the lifting-bar *c* carries antifriction-rollers *c²*, which travel along the face of the standards *i* and so resist the side strain which would be brought upon the lifting-bar. This peculiar way of mounting the lifting-bar 95 and cam forms the subject-matter of a separate application filed April 2, 1897, Serial No. 630,412. The cam illustrated is one well suited for the forming of the mold and illustrates the preferable way of obtaining the pec- 100 cular jarring action above referred to, having a series of cam-arms *l¹ l² l³*, which have short strokes, while the cams *l⁴ l⁵ l⁶* have long strokes, the length of the throws of these re- 105 spective arms being regulated according to the mold to be formed, and, if desired, either the cam-arms giving short strokes or those giving long strokes, respectively, can be made with gradually-increasing length of stroke to 110 each arm. This is generally desirable in connection with the long strokes, where each packing stroke will increase in length, and therefore give a heavier jar, the last stroke being the longest and giving the heaviest jar. It will be noticed that each cam-arm is formed 115 of an inclined face *l⁷*, by which the lifting-bar is raised, and a straight or practically radial face *l⁸*, which permits the bar to drop without contact with the cam until the jarring-table strikes the anvil-block *b*. The lifting-bar is 120 sufficiently short to prevent the roller *c'* from touching the cam when its reaches its lowest position, so that injury to the roller is pre- 125 vented. In Fig. 5 I have shown another means of obtaining strokes of different length, this being accomplished by means of a cylinder to be operated by steam or other fluid, the cylinder being supported under the platform *a* in such position that the lifting-bar *c* forms a continuation of the piston-rod. The cylin- 130 der *C* has a suitable valve-box *C'* for controlling its movement, and, as above stated, the

lifting-bar c is made in one piece with the piston C^2 . When so constructed, the strokes of the piston-rod can be regulated by hand or any other suitable way to give the desired jar.

- 5 The jarring-table d is generally formed of metal and needs no particular description except in connection with the yoke for holding the parts thereto, as hereinbefore described. The pattern-plate e , with its pattern e' , rests 10 directly upon this table, while the flask f and reservoir g are of the ordinary or any suitable construction. Above the flask f is the guided follower h , which, as shown in the drawings, has a central recess h^2 , corresponding 15 substantially in shape to the pattern e' , this guided follower having rigidly secured thereto the guide-stem h' , which moves within the guide-tube k' , forming part of the yoke k , a spring-pawl h^3 holding the follower up 20 within the guide-box when not in use. To provide for the proper clamping of the parts upon the table, the yoke has either the hollow box k^2 or the guide-bars k^3 , extending down therefrom around or on each side of the 25 follower h and resting upon the top of the reservoir g and so providing for the clamping of these parts to the jarring-table, the yoke k having the swinging clamp-bars k^4 depending therefrom and engaging with the table d 30 in any suitable way. In the construction illustrated the table d has slots d' formed in the side thereof, and these yoke-bars k^4 enter the slots sidewise. They carry at the ends thereof any suitable tightening devices for clamping 35 the yoke to the table, such as the cams or eccentrics k^5 , in the preferable construction there being two such cams, one on each side of each yoke-bar, the cams having the arms k^6 extending out therefrom and connected by 40 the cross-arm k^7 , so that when the yoke-bars k^4 are swung sidewise into the slots d' the operator, by pushing down upon the arms k^6 will turn the cams and clamp the yoke to the table. In this way he holds firmly to place 45 not only the yoke, but the pattern with its plate, the flask, the reservoir, and the guide-box k^2 , inclosing the follower h , so clamping all the parts rigidly together ready for forming the mold. The follower-guideway k' extends 50 up a sufficient distance to provide for properly guiding the follower by means of its guide-bar h' , and at the upper end thereof has bearings m' , in which is mounted the eccentric m , which acts as a retainer for the 55 follower h to prevent its upward movement after the jar, this eccentric being mounted, as shown, to one side of a vertical line through the guideway k' , so that it has a tendency to drop to one side under the jar, and as the follower h descends upon the jarring stroke the 60 eccentric will through the same jarring stroke turn in its bearing as far as the upper end of the guide-bar h' of the follower will permit and will then prevent the follower guide-bar h' from rising, so retaining it in position and 65 preventing any reacting of the follower which

might occur on the natural rebound from the jar. The guideway k' of the clamp is split a sufficient distance to permit of all necessary swing of this eccentric.

The eccentric m has an arm m^2 , which forms a weight giving it a tendency to follow down after the guide-bar h' and which has another advantage, as it provides an easy way for withdrawing the eccentric and for lifting off 70 the clamping-yoke and follower when the mold is finished. A simple and handy way of arranging these parts is shown in the drawings. The clamping-yoke, with its follower and other parts carried thereby, is hung from a 75 rope n , which passes around pulleys $n' n^2$ and carries a weight n^3 , which substantially counterbalances the yoke. Suitable loose weights may of course be added to the weight n^3 , as shown, according to the weight of the yoke 80 and follower employed. These parts are thus held up out of the way until needed, when to lower the yoke I provide the pulley p' , around which the rope p passes, being either connected to the rope n or to the weight, the rope 85 p extending down in position for the operator and having either the hand-stirrup p^3 or the foot-stirrup p^4 in such position that it can be easily grasped, and by pressure upon the same the weight n^3 be raised, which will permit the 90 descent of the yoke and the securing of the same in proper position for making the mold.

While the cam or eccentric m forms an efficient retaining means for the mold-follower, any suitable form of retainer may be employed, that shown in Fig. 5 being a ratchet mechanism, the follower q having the guide-bar q' , provided with a ratchet-rack q^2 on one face thereof, while the clamping mechanism carries a spring-operated pawl q^3 , mounted 100 on the eccentric m , which will take into the rack of the guide-bar and will hold the same from upward movement upon the descent of the follower upon the jarring stroke. This figure also shows another change in detail, the clamping-yoke having its standards r secured to the jarring-table and its clamping-bar r' mounted on one of said arms and swinging over and engaging the other arm and being forced downwardly by a hand-nut r^2 upon 115 this arm, so as to clamp the parts firmly upon the table.

The means for guiding the follower may be varied as desired, an example of other guiding means being shown in Fig. 6, in which a 120 reservoir s , of somewhat greater length than the ordinary reservoir, is employed and the follower s' has extending around or rising at certain points on its outer edge vertical guides s^2 , extending upwardly and guiding the movement of the follower through their alinement with the inner walls of the reservoir. To prevent rebound of the follower or hold it to the place to which it is jarred, it can carry movable weights s^3 , which are preferably arranged to 125 fit around the center post s^4 , to which is attached the rope s^5 , passing upwardly over the

pulley s^6 for raising the follower out of the reservoir.

Some of the features shown in Figs. 5 and 6 form the subject-matter of a separate application of even date herewith, Serial No. 629,918.

When the apparatus illustrated in Figs. 1 to 4 is employed, the usual course in forming molds is as follows: The jarring-table d of course rests normally upon the anvil-block b , while the clamp-frame k , held by the counter-weight n^3 , is held up out of the way of the workman. To make a mold, the operator places the flask upon a pattern-plate and sifts a certain amount of mealy sand over the pattern to fill as well as possible the different depressions therein and then places the reservoir g upon the flask f and fills the reservoir with sand. He then draws down upon the rope p by the hand-stirrup p^2 or foot-stirrup p^3 , which raises the weight n^3 and permits the clamping-frame k , carrying the guide-block h , to descend. He then brings the clamping-frame into position, so that the box k^2 , in closing the guide h , fits upon the top of the reservoir g , and he swings the bars k^1 into the slots d of the jarring-table and presses down upon the cam-arms k^6 , and so clamps all the parts—clamp-frame, reservoir, flask, and pattern-plate—firmly to the jarring-table. The apparatus is then ready for the forming of the mold, and the follower h is freed, so that it can drop upon the sand in the reservoir g when the apparatus is ready to form the mold. Power is then applied to rotate the cam l , which through its several cam-arms imparts the necessary jars to pack the sand within the flask and form the mold. Where the irregular form of cam illustrated in Figs. 1 and 2 is employed, the first operation will be to impart a few short jars to the sand within the flask and reservoir, which will distribute the sand over the pattern and into the smallest recesses thereof, it being found that while a heavy jar in forcing down a large bulk of sand may permit bridging over the delicate parts of the pattern, yet that a few short jars will properly fill the sand into the smallest depressions and cause it to conform to the delicate parts of the pattern, and so prepare it more perfectly for the actual packing jars. This is the action of the first three strokes imparted by the cam l , and as a result of these distributing strokes where the guided follower having a recess therein conforming, substantially, to the pattern is employed this follower will descend with the sand, which will be permitted to rise under the rebound of the jars into the recess h^2 there-60 of, while the lower portions of the follower conform to the space around the pattern, so that the body of sand around and above the pattern is of substantially the same thickness above both the pattern and the space around the pattern, the body of sand being brought to this condition before the heavy jarring strokes for packing are imparted thereto.

Where the sand is in this condition and where the guided follower held from rebound is employed, a few long jars will properly pack the sand within the mold, and these are obtained by the long cam-arms of the cam l , which operate to raise the jarring-table through the lifting-bar c and permit the same to drop upon the anvil-block b and impart such long jars, while the follower h descends at each jar and is sustained against rebound, and therefore holds the sand against such rebounding action, which is natural to it, so that in this way a solidly and evenly packed mold is obtained. During this operation the lift imparted to the jarring-table and parts carried by it is in a true vertical line, as the lifting-bar passing up through the anvil-block is properly guided and is perfectly free in its descent to permit the direct vertical drop of the table, so that all liability of side movement when the jar is imparted to the sand is done away with and the sand will pack by direct vertical movement and the formation of soft spots on one or the other side of the pattern prevented. In case of wear on this lifting-bar provision is made to take this up by means of the guide-blocks b^2 , above referred to, and at the same time the rollers c^2 , traveling on the guide-face of the standards i , resist any tendency to side movement of the lower or free end of the lifting-bar under pressure of the cam. When the jars are imparted to the table, the follower h of course descends under the influence of the jar; but it cannot cant or move out of its proper course, because it is properly guided, as by the guide-bar h^1 , and it cannot rebound, because the retainer, such as the eccentric m , turning under the jarring action holds down the guide-bar and prevents its rising again if there be any such tendency, acting therefore as a retainer for the follower through such guide-bar. During the formation of the mold the operator has through his hand or foot power to hold up the weight n^3 , and thereby permit the weight of the cam-frame and its follower to aid in the jarring action, and when the mold is completed the operator simply frees the clamp-arms k^1 through the movement of the cams k^5 and draws them out of the slots d' , and he then permits the weight n^3 to raise the clamping apparatus and follower out of the way, the follower being either at that time or before making the next mold raised to be engaged by the pawl k^3 and held up out of the way, so that the parts can be adjusted in making another mold. He then removes the reservoir, cuts off the surplus sand, and lifts the mold, with the flask and pattern, from the table, withdraws the pattern, and proceeds to form another mold in the way above described. In the use of the apparatus shown in Fig. 5 the operation is practically the same, differing only in the preparation for the making of the mold and the slight difference of mechanism above described, and in the making of the mold the desired short distributing jar-

ring strokes can be first imparted to the jarring-table and afterward the necessary long packing strokes with effect the same as that above described. In this operation the 5 ratchet-rack q^2 on the guide-bar q' slips past the pawl q^3 , which, however, catches in the rack and prevents backward movement of the guided follower, so retaining the follower in the lowest position to which it is moved by 10 the jarring stroke. In the apparatus shown in Fig. 6 there is substantially the same action, the follower being guided downwardly and prevented from canting by the guides traveling along the inner face of the reservoir, while the follower can be sufficiently 15 weighted to retain it in place and to prevent the rebound of the sand. In this way I am enabled to form more perfect molds by the jarring process, to improve that process in 20 important particulars, and to overcome difficulties encountered in the process as heretofore practiced which affected both the way of working and the resultant molds.

The method disclosed herein is not claimed 25 in this application, but is claimed in a division of this application filed February 6, 1901, Serial No. 46,161.

What I claim as my invention, and desire 30 to secure by Letters Patent, is—

30 1. The combination of a jarring-block having a central passage through the same, a jarring-table resting on said block, a lifting-bar connected to said table and passing through said block, lifting mechanism operating upon 35 said lifting-bar below the jarring-block, and adjustable guides within the jarring-block for controlling the movement of the lifting-bar, substantially as set forth.

2. The combination of a jarring-block having 40 a central passage through the same, a jarring-table resting on said block, a lifting-bar connected to said table and passing through said block, lifting mechanism operating upon said lifting-bar below the jarring-block, horizontal slots formed in the jarring-block, and 45 guide-blocks fitting in said slots and engaging with the lifting-bar, substantially as set forth.

3. The combination of a jarring-block having 50 a central passage through the same, a jarring-table resting on said block, a lifting-bar connected to said table and passing through said block, lifting mechanism operating upon said lifting-bar below the jarring-block, horizontal slots formed in the upper part of the 55 jarring-block and in the lower part of the jarring-block respectively, and guide-blocks fitting in said slots and engaging with the lifting-bar, substantially as set forth.

60 4. The combination of a jarring-block, a jarring-table, and a lifting-cam operating to raise said table and permit it to drop upon the jarring-block, said cam having one or more short cam-arms and one or more long cam-arms, substantially as and for the purposes set forth.

65 5. The combination of a jarring-block and

a jarring-table, a flask, a reservoir, and a follower adapted to enter the reservoir and hold the sand from rebound in jarring, and a guide 70 connected to and above the follower-body to hold the same horizontal, substantially as set forth.

6. The combination of a jarring-block, a jarring-table, a flask, a reservoir, a clamping-frame above the reservoir and carrying a guideway, and a follower having a guide entering such guideway, substantially as set forth.

7. The combination of a jarring-block, a jarring-table, a flask, a reservoir, a clamping-frame adapted to be secured to the table and carrying a guideway and having a support 80 engaging with the reservoir, and a follower within said support adapted to enter the reservoir and having a guide entering said guideway, substantially as set forth.

8. The combination of a jarring-block, a jarring-table, a flask, a reservoir, a guided follower and a retainer for said follower arranged to prevent back movement thereof 85 during the jarring operation, substantially as set forth.

9. The combination of a jarring-block, a jarring-table, a flask, a reservoir, and a clamping-frame engaging the reservoir and having depending bars detachably engaging with the jarring-table, substantially as set forth.

10. The combination of a jarring-block, a jarring-table having slots in the edges thereof, a flask, a reservoir, and a clamping-frame having depending arms entering said slots and carrying cams engaging with the lower face of the jarring-table, substantially as set forth.

105 11. The combination of a jarring-block, a jarring-table, a flask, a reservoir, a clamping-frame carried by said table and having a guideway thereon and a bearing above the guideway, a follower having a guide-bar entering said guideway and a cam mounted in said bearing and contacting with the upper end of the guide-bar, substantially as set forth.

115 12. The combination of a jarring-block, a jarring-table, a flask, a reservoir, a clamping-frame, a pulley above the table, a rope connected to the frame and passing over the pulley and a counterbalancing-weight connected to said rope, substantially as set forth.

120 13. In sand-molding apparatus, the combination of a jarring-block, a jarring-table, a flask, a reservoir, a clamping-frame, a pulley above the table, a rope connected to the frame and passing over the pulley and a counterbalancing-weight connected to said rope, and an operating-rope adapted to raise the weight and permit the descent of the clamping-frame, substantially as set forth.

13. The combination of a jarring-block, a jarring-table, a flask, a reservoir, a clamping-frame, a pulley above the table, a rope connected to the frame and passing over the pulley and a counterbalancing-weight connected

to said rope, and an operating-rope adapted to raise the weight and permit the descent of the clamping - frame and having stirrups therein, substantially as set forth.

5 15. The combination of a jarring-block, a jarring-table, a flask, a reservoir, a jarring-frame carrying a follower and having a bearing, a cam mounted in said bearing and engaging with the follower and having an arm thereon, a pulley above the jarring-table, a rope connected to said cam-arm and passing over said pulley, and a counterbalancing-weight connected to the rope, substantially as set forth.

10 16. The combination of a jarring-block, a jarring-table, a flask, a reservoir, a single

clamping means arranged to secure both the reservoir and flask to the table, and a guided follower adapted to enter the reservoir, substantially as set forth.

20

17. The combination of a jarring-block, a jarring-table, a flask, a reservoir, a follower adapted to enter the reservoir and a retaining device arranged to engage therewith and prevent back movement during the jarring 25 operation, substantially as set forth.

In testimony whereof I, the said STEPHEN JARVIS ADAMS, have hereunto set my hand.

STEPHEN JARVIS ADAMS.
